UNITED STATES PATENT OFFICE.

CLAYTON W. KNAPP, OF CLEVELAND, OHIO.

DESIGN FOR A SACHET DEVICE.

Application filed June 11, 1928. Serial No. 27,081. Term of patent 3½ years.

To all whom it may concern:

Be it known that I, CLAYTON W. KNAPP, a citizen of the United States, residing at Cleveland, in the county of Cuyahoga and State of Ohio, have invented a new, original, and ornamental Design for a Sachet Device, of which the following is a specification, reference being had to the accompanying drawing, forming part thereof.

The figure is a perspective view of a sachet device showing my new design.

I claim:

The ornamental design for a sachet device as shown.

Signed by me, this 26th day of May, 1928.

CLAYTON W. KNAPP.
